UNITED STATES PATENT OFFICE.

HANNEH BRANCH, OF NORTH SAN JUAN, CALIFORNIA.

COUGH REMEDY.

SPECIFICATION forming part of Letters Patent No. 267,738, dated November 21, 1882.

Application filed September 18, 1882. (No specimens.)

To all whom it may concern:

Be it known that I, HANNEH BRANCH, of North San Juan, county of Nevada, State of California, have invented a new and useful 5 medical compound to be used in cases of coughs, colds, asthma, whooping-cough, and all diseases of the throat and lungs, of which the following is a specification.

My compound consists of the following ingredients, combined in the proportions stated, viz: common tar, one table-spoonful; pure honey, three table-spoonfuls; yolks of three hen's eggs; extract of licorice, dissolved in port-wine, one table-spoonful; port-wine, one-half pint.

The manner in which I prepare this compound is as follows: Having first dissolved the licorice in a small quantity of the best port-wine, I beat the eggs, tar, and honey together and add one table-spoonful of the dissolved licorice, and then beat all together with a knife until they are thoroughly mingled. I then add the half-pint of the best port-wine and beat all together again. This 25 mixture I then bottle and seal. The directions I would urge for its use are these: one tea-spoonful morning, noon, and night, to be taken immediately before eating. Its effect is to loosen the phlegm, to lubricate and heal the throat, to strengthen and enrich the blood, 30 and generally to relieve the local parts and tone up the system.

I am aware that heretofore ground licorice-root has been saturated with a mixture of tar, glycerine, sugar, and alcohol, and used medicinally, and I distinctly disclaim the same.

Having thus described my invention, what I claim as new, and desire to secure by Letters Patent, is—

The herein-described medical compound for 40 coughs, colds, asthma, and throat and lung affections generally, consisting of tar, honey, egg-yolks, licorice, and port-wine, substantially in the proportions specified.

In witness whereof I hereunto set my hand. 45

HANNEH BRANCH.
